William J. Dufficy

INVENTOR

BY Victor J. Evans

ATTORNEY

WITNESS:

John J. Dufficy

UNITED STATES PATENT OFFICE

WILLIAM J. DUFFICY, OF DENVER, COLORADO

BAR RATCHET FOR SCREEN ROLLERS

Original application filed July 28, 1927, Serial No. 209,340. Divided and this application filed March 12, 1928, Serial No. 261,112. Renewed April 24, 1929.

This invention relates to a means for holding a spring roller against movement, the general object of the invention being to provide the roller with an annular row of holes in one end, with a manually movable bar having one end shaped to engage any one of the holes to hold the roller in adjusted position. This invention is more particularly designed for use with the window screen and its spring roller shown in an application filed by me on July 29, 1927, Serial No. 209,340.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a view, partly in section, of the upper part of a window, with a screen carried by a spring roller and showing the improved means for holding the roller in adjusted position.

Figure 2 is a section on line 2—2 of Figure 1.

Figure 3 is a view of the manually operated bar.

Figure 4 is a view of the guide for the bar.

In these views, A indicates the frame and B the sash slidably mounted therein. The frame is formed with a chamber 1 in which is journaled a spring roller 2 to which one end of a screen 3 is connected. This screen passes through a slot 4 formed in the bottom of the chamber and the lower end of the screen has attached thereto a member which is provided with a pair of keeper eyes which are adapted to be engaged by parts of a latch rod slidably mounted in the upper end of the sash B and which is movable longitudinally through means of a handle 5 attached to the rod and extending through a slot 6 formed in the sash. By moving this rod through means of its handle 5, the screen can be attached to or detached from the sash. The

above described arrangement forms the subject matter of the application before mentioned.

In order to prevent the spring in the roller from pulling the screen to the top of the window opening when it is released from the sash, I provide ratchet means for preventing movement of the roller. Such means comprise an annular row of holes 7 formed in one end of the roller 2 and a bar 8 which has its lower end bent at right angles to form a shaft 9 which is journaled in a bracket 10 fastened to a part of the frame, the upper end of the rod being bent, as shown at 11, to engage any one of the holes 7. The end of the shaft part 60 9 passes through the face of the frame where it receives a knob 12 so that the rod can be manipulated to place its end 11 into or out of engagement with one of the holes 7. An elongated bracket 13 is fastened to the frame 70 and forms a guide for the rod 8 during its movement.

From the foregoing it will be seen that by turning the knob 12 and the part 9, the extremity 11 of the rod 8 can be moved into engagement with one of the holes 7 so as to prevent turning movement of the roller under the action of its spring. This will hold the screen stationary while it is being attached to or detached from the sash. 80

It is thought from the foregoing description that the advantages and novel features of my invention will be readily apparent.

It is to be understood that I may make changes in the construction and in the combination and arrangement of the several parts, provided that such changes fall within the scope of the appended claims.

What I claim is:—

1. Means for holding a spring roller 90 against turning movement comprising a rod having one end shaped to engage any one of a number of holes in one end of the roller, the other end of the rod being bent at right angles to form a shaft, a knob on the end of this shaft part and means for rotatably supporting the shaft part.

2. In combination with a frame having a window opening, and a spring roller carrying a screen, means for holding the roller in 100

adjusted position, comprising a rod having one end bent to form a shaft, a bracket fastened to the frame of the window and in which the shaft part is rotatably mounted, the end of the shaft part extending through the frame, a knob on the extended part, the other end of the rod being bent, one end of the roller having a plurality of holes therein, any one of which is adapted to receive the bent end of the rod and a guiding bracket for the rod fastened to the frame.

In testimony whereof I affix my signature.
WILLIAM J. DUFFICY.
